Wedgwood and Sons, Ltd., rec'd Aug. 21, 1935, page XXXII, item 2.

To all whom it may concern:

Be it known that I, Eva S. Zeisel, a citizen of the United States of America, residing at New York city, in the county of New York and State of New York, have invented a new, original, and ornamental Design for a Baker, of which the following is a specification, reference being had to the accompanying drawing, forming part thereof.

Fig. 1 is a side elevation of a baker showing my new design,

Fig. 2 is a longitudinal cross-section, and

Fig. 3 is a bottom plan view on a smaller scale thereof.

I claim:

The ornamental design for a baker, as shown.

EVA S. ZEISEL.
